UNITED STATES PATENT OFFICE.

MATTHEW LECLOUX, OF BAYONNE, NEW JERSEY.

DESIGN FOR A GAME-BOARD.

SPECIFICATION forming part of Design No. 31,908, dated November 28, 1899.

Application filed November 1, 1899. Serial No. 735,537. Term of patent 7 years.

To all whom it may concern:

Be it known that I, MATTHEW LECLOUX, of Bayonne, in the county of Hudson and State of New Jersey, have invented and produced 5 a new and original Design for a Game-Board, of which the following is a full, clear, and exact specification.

Reference is to be had to the accompanying drawings, forming a part of this specification, 10 in which similar characters of reference indicate corresponding parts in both the views.

Figure 1 is a plan view of a game-board, showing my design; and Fig. 2 is a sectional side elevation of the same on the line 2 2 in 15 Fig. 1.

The design in its entirety consists of concentric fields A and B, appearing on the face of the board C and having circular spaces D and E, respectively, and a space D' appearing 20 in contrast to the other spaces D and E,

and the adjacent spaces in each field being joined by lines F, the alternate spaces D being joined by radial lines G to the adjacent spaces E, and the inner ends of the spaces E being joined by radially-extending lines H, 25 leading to a central opening I in the board.

The leading feature of the design consists of a board having a central opening and concentric fields having defined spaces in the fields, one of the spaces in the outer field contrasting with the other spaces. 30

Having thus fully described my invention, I claim as new and desire to secure by Letters Patent—

The design for a game-board herein shown 35 and described.

MATTHEW LECLOUX.
